UNITED STATES PATENT OFFICE.

MONTE WELSH, OF SAN ANTONIO, TEXAS.

PHOTOGRAPHIC-PRINTING MACHINE.

Application filed April 23, 1920. Serial No. 376,037.

To all whom it may concern:

Be it known that I, MONTE WELSH, a citizen of the United States, residing at San Antonio, in the county of Bexar and State 5 of Texas, have invented a new and useful Photographic-Printing Machine, of which the following is a specification.

The device forming the subject matter of this application is a photographic printing apparatus, of that general form shown 10 in my prior Patent No. 1,186,719, granted on the 13th day of June, 1916.

The device forming the subject matter of this application contemplates general improvements in the structure shown in my 15 former patent, these improvements being made manifest as the description is proceeded with.

Specifically, one object of the invention is 20 to provide novel means for pressing the mask against the film or negative.

Another object of the invention is to provide novel means whereby the film may be raised and lowered, so that the film will 25 cooperate with the opening in the mask.

A further object of the invention is to provide novel means for operating and controlling a ground glass which serves to diffuse the light.

30 A further object of the invention is to provide novel means for operating the switch which controls the current to the lamp.

The invention aims, further, as above intimated, to improve generally and to enhance 35 the utility of devices of that type hereinafter described.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention 45 shown can be made without departing from the spirit of the invention.

In the accompanying drawings:—

Figure 1 shows in side elevation, a device constructed in accordance with the invention, 50 parts being broken away and parts appearing in section; Figure 2 is a top plan of the machine; Figure 3 is an end elevation; Figure 4 is a sectional detail showing the presser block which is carried by one of the hinged leads; Figure 5 is an elevation showing in detail, parts of the paper holding mecha-

nism; Figure 6 is an elevation looking at the negative support, parts of the device having been removed; Figure 7 is a sectional detail showing a portion of the means whereby the 60 film is guided and controlled, the view depicting the relation existing between the mask, the film and the panel; Figure 8 is a detail showing the switch; Figure 9 is a fragmental vertical section, parts being omitted and broken away; and Figure 10 is a fragmental elevation showing a portion of the paper holding means.

In the drawing, there appears a base 1, carrying an upstanding negative holder 2 in 70 the form of a plate or board having an opening 3. A recess 4 is formed in the holder 2 about the opening 3 and in the recess, a panel 5, preferably a glass plate, is seated, the panel being held in place by buttons 6 on the holder 2. Spring arms 7 are attached at 75 8 to the base 1 and tend to press against the holder 2. Studs 23 are mounted in the arms 7 and extend slidably through the negative holder 2, nuts 24 being mounted on the studs, 80 and compression springs 25 being interposed between the nuts and the holder 2. The tendency of the springs 25, obviously, is to draw the arms 7 toward the holder 2, it being possible to adjust the effort of the springs 85 25, by rotating the nuts 24. Referring to Figure 7 it will be observed that the arms 7 are supplied with guides 9 disposed adjacent to the negative holder 2. The arms 7 are provided with vertical sockets 12 adapted to 90 receive beads 11 on the edges of a mask 10, the beads being inserted downwardly into the sockets. The numeral 14 denotes a film, passing across the guides 9 and extended between the mask 10 and the panel 5.

A means is provided whereby the film 14 may be raised and lowered, to locate the film properly with respect to the opening 35 in the mask 10. With this end in view, guide plates 15 are attached to the edges of the negative holder 2 by securing elements 16, slides 17 being mounted to reciprocate between the guide plates 15 and the edges of the negative holder, the slides having elongated slots, wherein the securing elements 16 are received. The slides 17 having projecting hook-shaped brackets 19 and are supplied with racks 20 meshing into pinions 21 carried by a shaft 22 mounted to rotate on the negative holder 2 and supplied with a knob 26 whereby the shaft may be manipulated conveniently.

It will be understood that when the shaft 22 is rotated by means of the knob 26, the pinions 21 cooperating with the racks 20, will raise or lower the slides 17, the brackets 5 19 carrying the film 14 upwardly and downwardly, and locating the film properly with regard to the opening 35 in the mask 10.

One improvement contemplated in this application, is the provision of means whereby 10 the mask 10 may be pressed against the film 14. The means above alluded to comprises a pair of bearing brackets 27 mounted on the holder 2, a shaft 28 being journaled in the brackets. A loop-shaped spring 29 is carried 15 by the shaft 28 and supports a presser arm 30, adapted to engage the mask 10. A latch 31 is mounted on the negative holder 2 and is supplied with a seat 32 adapted to engage a crank 33 at one end of the shaft 28, the 20 other end of the shaft being supplied with a crank 34.

In operation, rotation may be imparted to the shaft 28 through the instrumentality of the crank 34, the member 30 being pressed 25 against the mask 10 and the spring 29 being put under tension. When the shaft 28 is rotated as aforesaid, the crank 33 interlocks with the seat 32 of the latch 31 and thus the member 30 is held yieldingly but 30 firmly against the mask 10 so as to press the mask against the film 14 and to hold the film between the mask and the transparent panel 5.

As in my prior patent hereinbefore mentioned, a main leaf 36 is hinged at 37 to the base 1, an auxiliary leaf 38 being hinged at 39 to the upper edge of the main leaf 36. A shaft 40 is mounted to rock in bearings 41 on the base 1 and is provided with a crank 40 42 connected by a pitman 43 with the auxiliary leaf 38, there being a buffer 44 on the base 1, wherewith the pivotally connected ends of the crank 42 and the pitman 43 are adapted to engage, when the pitman 43 45 moves downwardly and rearwardly an unusual amount. The shaft 40 is supplied with a crank 45 pivoted at 46 in a lever 47. One end of a link 48 is pivoted to the lever 47, the other end of the link being pivoted to the 50 base 1. A latch 49 is mounted on the base 1 and is adapted to cooperate with the lever 47.

The numeral 50 denotes a back plate carrying studs 51 slidably mounted in the leaf 38 55 and provided with nuts 52 cooperating with the outer surface of the said leaf. Compression springs 53 surround the studs 51 and about against the leaf 38 and against the back plate 50, the springs serving to advance the back plate. The back plate 50 is supplied 60 along its opposite edges with flanges 54 and 55. The numeral 56 marks a presser head supplied on one surface with a pad 57 and carrying, upon its opposite surface, a plate 65 58 having fingers 59 adapted to be received

in openings in the flange 55 of the back plate 50. Latches 60 are mounted to swing on the presser head 56 and are united by a connecting strip 62, one latch 60 having a handle 61.

The finger 59 may be inserted through the flange 55, the latches 60 being operated through the instrumentality of the handle 60 and the connecting strip 62, both latches 70 engaging the back plate 50 as clearly shown 75 in Figure 4, the latches engaging the back plate adjacent to the flange 54, against which one edge of the plate 58 abuts. The presser head 56 is connected releasably with the plate 50 and is yieldingly supported, by the 80 springs 53, with respect to the leaf.

The sensitized paper is held, by a means to be described hereinafter, on the pad 57 of the presser head 56, and the sensitized paper may be pressed against the mask 10 by depressing the free end of the lever 47 and engaging the lever with the latch 49, a rocking movement being imparted by the crank 45 to the shaft 40, the crank 42 and the pitman 43 swinging the leaves 36 and 38 until 90 the presser head 56 exercises its function as hereinbefore explained, the springs 53 serving to support the presser head yieldingly.

A clamp plate 65 slides in contact with one edge of the presser head 56 and is provided with a flange 66 cooperating with the working surface of the presser head, that is, with the pad 57, to hold the papers thereagainst. The clamp plate 65 has inclined slots 67 receiving guide pins 68 mounted in 100 the edge of the presser head 56. A shaft 69 is mounted to rock in bearings 70 on the outer surface of the presser head 56 and is provided with an intermediate finger 71 adapted to cooperate with a cam 72 carried 105 by the leaf 36. The shaft 69 has a crank arm 73 connected by a link 74 with the clamp plate 65. A spring 75 is connected at one end to the presser head 56 and is connected at its other end with the finger 71. The spring 75 110 tends to rock the shaft 69 in the bearings 70, the crank arm 73 and the link 74 drawing the clamp plate 65 endwise, a transverse movement being imparted thereto by the slots 65 and the pins 68, the flange 66 thus 115 being made to cooperate with the pad 57 and to hold one edge of the sensitized paper.

In operation, after the printing has been completed, and after the leaf 38 has been 120 swung downwardly and backwardly from the position of Figure 1, the finger 71 cooperates with the cam 72 and rocks the shaft 69, the arm 73 and the link 74 operating the clamp plate 65 so that its flange 66 no longer grips the paper. The paper, therefore, is released when the leaves 38 and 36 are swung backwardly by the operation of the lever 47 and attendant parts. The guide plate 76 may extend along one edge of the 125 presser head 56, at right angles to the clamp 130

plate 56, the guide plate 76 being in the form of an angle member if desired. One flange of the clamp plate 77 slides, as indicated in Figure 5, between the corresponding flange of the guide plate 76 and the presser head 56, securing elements 78 connecting the guide plate 76 with the presser head, and one flange of the clamp plate being slidably mounted on the securing elements. When

10 the leaf 38 and the presser head 56 are advanced toward the negative holder 2, the transverse flange of the clamp plate 77 cooperates with the pad 57 to aid in holding the paper, the clamp plate 77 being released, 15 as soon as the presser head 56 and the leaf 38 are swung backwardly away from the negative holder 2.

A casing 79 is connected with the base 1 and the negative holder 2, the base and the 20 negative holder constituting, to all intents and purposes, a part of the casing. Adjacent its upper edge and upon its sides, the casing 79 is provided with ventilating openings 80 which also serve to permit the operator to look into the interior of the casing. The casing 79 includes a top 81 to which a lid 82 is hinged as shown at 83, the lid having an extension 84 connected thereto by hinges 85, the extension 84 forming an inclined front for the casing, to the rear and above the negative holder 2. Guides 86 are carried by the lid 82 and in the guides 86, a slide 87 is mounted for reciprocation. A shaft 88 is journaled in the lid 82 and is 35 provided with an exposed handle 89. The inner end of the shaft 88 terminates in an arm 90 having a finger 91 mounted to move in a slot 93 formed in the slide 87. The guide 87 carries lamps 92.

40 It will be understood that when the shaft 88 is operated by means of the handle 89, the slide 87 may be moved forwardly and backwardly, so as to position the lamps 92 properly, with respect to the negative and 45 the sensitized paper.

A shaft 94 extends transversely of the casing 79 and is journaled therein. Within the casing 79, a shaft 94 carries a frame 95 supporting a plate or screen 96, made of 50 frosted glass or any other suitable material. Externally of the casing 79 the shaft 94 carries a handle 97.

By means of the handle 97, the shaft 94 may be rotated, the frame 95 swinging the 55 plate or screen 96 with respect to the lamps 92, so as to diffuse the light with respect to the negative.

The extension 84 of the lid 82 is provided with inwardly projecting flanges 98 to 60 which a screen 99 is pivoted or hinged as indicated at 100. The screen 99 may be swung backwardly and upwardly against the extension 84, as shown in Figure 9, and be held in that position by frictional engagement with projections 101 on the flanges 98.

If desired, the screen or shield 99 may be swung downwardly into the dotted line position of Figure 9 and when thus disposed, serves to protect the eyes of a person looking into the machine or watching the printing 70 operation. The shield 99 is of peculiar utility when a negative is not wide enough to extend entirely across the opening 3 in the holder 2.

A lamp 102 is mounted on the rear portion 75 of the casing 79 and is in circuit by means of a conductor 103, with the lamps 92. In the conductor 103 is interposed a knife switch mounted on the lower portion of the negative holder 2. The knife switch as indicated 80 in Figure 8 may include a contact member 105 and a pivotally mounted blade 106 constrained by a spring 107 into open-circuit relation with respect to the contact 105, the numeral 108 denoting a base in which a 85 plunger 109 slides, the plunger being adapted to cooperate with one end of the lever 106. The plunger 109 extends through the negative holder 2 and is slidably mounted therein, the rear end of the plunger lying 90 in the path of the leaf 36, as shown best in Figure 1 of the drawings.

When the leaf 36 is swung upwardly and forwardly, the leaf advances the plunger 109, the lever 106 is swung into engagement 95 with the contact 105, and thus the circuit, including the lamps 102 and 92 is closed. As soon, however, as the leaf 36 is swung backwardly, the plunger 109 is released, and the lever 106, under the compulsion of 100 the spring 107 breaks contact with the member 105, and opens the lamp circuit. The lamps, therefore, burn only so long as the leaves 36 and 38 and the presser member 56 remain in advanced positions.

Having thus described the invention, what is claimed is:—

1. In a device of the class described, a base; a negative holder on the base; a main leaf hinged to the base; a presser member 110 cooperating with the negative holder; means for connecting the presser member with the main leaf for hinged movement with respect to the main leaf; means for producing swinging movement of the main leaf with 115 respect to the base and for producing swinging movement of the presser member with respect to the main leaf; a paper clamp movable on the presser member; a cam on the main leaf; a shaft mounted to rock on 120 the presser member and provided with a finger cooperating with the cam; and means for connecting the shaft operatively with the paper clamp.

2. In a device of the class described a negative holder; a shaft journaled thereon and provided at its ends with cranks, one crank being an operating crank; a resilient presser arm cooperating with the holder and carried by the shaft; and a latch mounted on the 130

holder, the latch cooperating with the other crank to hold the presser arm in cooperating relation with respect to the holder.

3. In a device of the class described, a casing including a hingedly mounted front member, and including a negative holder located below the front member; and a shield hinged to the front member and adapted to be swung down into overlapping relation with respect to the negative holder, the front member and the shield having cooperating

parts serving to retain the shield when the shield is swung upwardly away from the negative holder.

In testimony that I claim the foregoing as my own, I have hereto affixed my signature 15 in the presence of two witnesses.

MONTE WELSH.
